UNITED STATES PATENT OFFICE.

LOUIS HENRY KNAPP, OF SYRACUSE, NEW YORK, ASSIGNOR OF ONE-THIRD TO WILLIAM E. JENKINSON, OF SYRACUSE, NEW YORK.

GUY-ROPE-CABLE CLAMP.

No. 919,026.

Specification of Letters Patent.

Patented April 20, 1909.

Application filed July 20, 1908. Serial No. 444,335.

To all whom it may concern:

Be it known that I, LOUIS H. KNAPP, a citizen of the United States, and a resident of Syracuse, in the county of Onondaga and State of New York, have invented a new and Improved Guy-Rope-Cable Clamp, of which the following is a full, clear, and exact description.

At the ends of guy wires or cables, such as 10 used for staying telegraph poles, stacks, etc., it is necessary to form loops by means of which the guy wires or ropes are secured in position.

The object of this invention is to provide a 15 clamp of simple construction, which can be quickly applied to clamp the main part of the cable to the end of the loop.

The invention consists in the construction and combination of parts to be more fully 20 described hereinafter and particularly set forth in the claim.

Reference is to be had to the accompanying drawings forming a part of this specification, in which similar characters of reference 25 indicate corresponding parts in all the figures.

Figure 1 is a perspective of a clamp constructed according to my invention, and represents the same as forming a loop; Fig. 2 is a longitudinal section through the clamp 30 taken at one side and showing one of the channels which receives the cable, and showing also the seat for the wedge which jams the cable in position; Fig. 3 is a longitudinal section of one of the wedges, that is, the 35 wedge which coöperates with the side of the device shown in Fig. 2; Fig. 4 is a perspective of this wedge; and Fig. 5 is a cross section through the device.

Referring more particularly to the parts, 40 1 represents the body of the device, which is in the form of a block of elongated rectangular shape. This block is formed with two longitudinally-disposed gutters 2 and 3, which are separated by a partition wall 4, 45 which extends throughout the length of the block. The side walls of the gutters 2 and 3 diverge outwardly toward the lower face of the block, as indicated in Fig. 5, and these faces are formed with grooves 5 which are 50 under-cut so as to present inclined overhanging shoulders or wedge seats 6. These wedge seats incline downwardly longitudinally of the block, as indicated in Fig. 2. The lowest point of the wedge seat is dis- 55 posed toward the direction in which the cable

section extends, hence, the wedge seats incline in opposite directions, the depressed end of one being disposed opposite to the elevated end of the other.

In the bottom of the gutters 2 and 3, 60 rounded channels 7 are formed, which are adapted to receive the parts 8 and 8^a of the cable, to form a loop 9, as indicated in Fig. 1. The cable after being placed in the channels is clamped firmly in position by wedges 10 and 11. The form of these wedges is very 65 clearly shown in Fig. 4. They are similar in form and in cross section conform substantially to the cross section of the gutters in which they are received. They have side 70 cheeks 12 which seat in the grooves 5, as indicated, and these side cheeks taper, corresponding with the incline of the shoulders 6. In this way they are made to present inclined shoulders 13 which seat upon the shoulders 75 6, as will be readily understood. The butt end of each wedge is provided with a projecting toe 14 which is adapted to be struck by a hammer or maul in seating the wedge. On their lower sides the wedges are provided with 80 channels 15 which are disposed opposite to the channels 7, as indicated in Fig. 5. Although the channels 7 are of plain cylindrical bore, the channels 15 are formed with a plurality 85 of longitudinally disposed inclined cheeks or faces 16 which are rounded at their ends so that they form a plurality of equidistant clamping shoulders 17. The elevated part of the inclined cheeks is disposed toward the forward end of the wedge, as indicated in 90 Fig. 3. From this arrangement, when the wedges are driven into position the cheeks lying on the upper faces of the cable do not offer great resistance to the driving of the wedges. The abrupt shoulders 17, however, 95 tend to prevent the loosening of the wedges once they have been driven into position.

It will be noted that the tension in the cable tends to tighten the wedges in position, as the force exerted by the cable on the 100 shoulders 17 is in the direction of movement which seats the wedges.

Having thus described my invention, I claim as new and desire to secure by Letters Patent:

A cable clamp, comprising a block having longitudinal gutters formed therein with a partition wall therebetween, the side walls of said gutters having inclined wedge seats, said gutters having bottoms disposed in a 110

plane substantially at right angles to said partition wall and having channels therein adapted to receive the cable, and wedges having inclined shoulders on the sides thereof 5 engaging with said seats and having channels opposite said first channels and adapted to clamp the cable therebetween.

In testimony whereof I have signed my name to this specification in the presence of two subscribing witnesses.

LOUIS HENRY KNAPP.
